ALLEN GOMSTOK CO. INC.

Design for a cooking stove

Des. 873

Allen Comstock, of Quincy, Ill.
Letters Patent No. 873-Dated Mar. 10. 1857.

The Schedule referred to in these Letters Patent and marking
part of the same.

To all whom it may concern:

Be it known that I, Allen Com-
stock of Quincy, in the County of Adams and State of Illinois, have
invented or produced a new and original Design for a baking stove,
and I do hereby declare, that the following is a full and exact

description of the same, reference being had to the accompanying drawing which is a perspective view.

My design is for a stove denominated the "American Cooking Range" which words are cast in raised letters on the lower part of the front plate. The general shape of the stove is oblong, it being intended for burning wood of greater length than usual, and having three holes for cooking vessels in the front row over the fire. The principal features in the configuration are the projecting pilasters, two of which are in front and near the corners, and two others near the middle of the sides.

The corners of the stove are round and the several plates, pilasters, doors, top plate &c are surrounded by suitable mouldings. On each door of the fire chamber, and on the plate opposite the wood door, is cast in relief an altar loaded with fruit and flowers; on one end of the oven doors is a representation of the "Capitol" also in relief; and upon the side pilasters are reliefs of an oval niche surmounted by a fancy cross, also an ornament in similar style on the front pilasters.

The stove represented in the drawing is No. 4, but there are other sizes of substantially the same design.

What I claim and desire to secure by letters patent is,

The design and configuration of the several parts of the stove, in combination with the projecting pilasters, mouldings and ornaments in relief, substantially as specified and represented in the drawings.
